United States Patent Office.

THEODORE PURSE AND HENRY C. DRAPER, OF ASHLEY, MISSOURI.

Letters Patent No. 70,611, dated November 5, 1867.

IMPROVED SACK-FASTENER.

The Schedule referred to in these Letters Patent and making part of the same.

TO ALL WHOM IT MAY CONCERN:

Be it known that we, THEODORE PURSE and HENRY C. DRAPER, of Ashley, in the county of Pike, and State of Missouri, have invented certain new and useful improvements in Sack-Fasteners; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention relates to sack-fasteners, and consists in bending and hinging two pieces of wire or other suitable material, so that they may be made to embrace and securely hold the mouth of a sack. In the drawings—

Figure 1 is a plan view in perspective, and

Figure 2 is a view of the fastener as applied.

In constructing our sack-fastener, we take two pieces of wire, A B, of any desired size and length, suitable for our purpose. One of the pieces B we bend in bow-shape, and also so as to have an eye, *a*, and a hook, *b*, as shown in fig. 1. These two pieces A B we then hinge at C in any of the ordinary ways, so that they may move parallel with each other, and so that when they come together the hook *b* may readily be caught on to the piece A.

In using our sack-fastener, we gather up the mouth of the sack D, and then place the fastener about it by slipping the folds of the sack between the jaws of the fastener, and drawing the ends of the fastener together and locking them, as shown in fig. 2. The curved form of the piece B allows sufficient room for the folds or gathers of the sack. By means of the eye *a* we can attach the fastener to the sack D, so that it may be always ready for use in fastening the sack or in hanging it up, as well as secure against loss.

In this way we are able to provide a cheap and convenient ready fastener for sacks.

Having thus described our invention, what we claim, is—

The sack-fastener, consisting of the two pieces of wire A B, hinged or pivoted at C, when bent and arranged to operate substantially as described.

THEODORE PURSE,
HENRY C. DRAPER.
